WILLIAM A. BERNARD, OF NEW HAVEN, CONNECTICUT, ASSIGNOR TO THE WILLIAM SCHOLLHORN COMPANY, OF NEW HAVEN, CONNECTICUT, A CORPORATION OF CONNECTICUT.

HAND-TOOL.

1,164,981.

Specification of Letters Patent. Patented Dec. 21, 1915.

Application filed June 27, 1914. Serial No. 847,693.

To all whom it may concern:

Be it known that I, WILLIAM A. BERNARD, a citizen of the United States, residing in the city and county of New Haven and State 5 of Connecticut, have invented certain new and useful Improvements in Hand-Tools, of which the following is a full, clear, and exact description.

This invention relates to hand tools of the 10 lever handle type, such as pliers, pincers, nippers, and devices of like nature.

The invention has particular reference to tools of this kind in which there is a compound or multiple leverage for making the 15 tool as powerful as possible.

The primary object of the present invention is to provide a hand tool of the compound lever type which is relatively short and compact, and which possesses all of the 20 advantages of the compound leverage without being cumbersome and expensive.

To this end, the invention consists in the novel features and combinations of parts, more fully explained hereinafter.

25 In the accompanying drawing, Figure 1 is a side elevation of a tool embodying my improvement with the jaws opened; Fig. 2 is a view from the opposite side with the jaws closed; Fig. 3 is a top view of Fig. 1; 30 Fig. 4 is a transverse section through the pivot connecting the lever handles; and Fig. 5 is a fragmentary longitudinal section, partly in elevation, of the parts shown in Fig. 4.

35 I have shown my improvements as applied to a tool known as a "diagonal nipper", the jaws 6 of the tool being furnished with cutting edges 6^a arranged diagonally or obliquely of the lengthwise axis of the tool.

40 However, it will be understood that the form of the jaws is immaterial so far as my invention is concerned, and that the invention may be carried into effect with end nippers, pliers, pincers and various other tools. In

45 the form shown, the jaws 6 are formed on the forward ends of crossed lever members 7, which are pivoted together by a bolt 8 having a nut 9. The jaws are located in front of the pivot, and the levers are provided with shanks extending rearwardly behind the pivot, said shanks located in the

same plane. The jaws 6 are operated by means of handle levers 10, which are pivoted together at their forward ends by means of a pin 11, and are pivoted to the rear end 55 portions of the levers 7 intermediate of the ends of the levers 10 by means of the pins 12. The pivot 11 for the lever handles 10 is located between the rear portions of the levers 7. By pivoting the lever handles together 60 at their forward ends and pivoting them to the levers 7 in the manner stated, the levers 10 will act as levers of the second kind or order, the resistance or load being located between the fulcrum (11) and the points 65 where the power is applied, *i. e.*, the rear end portions of the lever handles.

In the example illustrated, the levers 10 are made of sheet metal bent up into U-shaped cross-section. The forward end 70 portion of each lever 10 is bifurcated or forked, as shown at 13, in order to straddle the rear end portion of the corresponding lever 7. The pins 12 are driven through both arms or branches of the fork, and 75 through the interposed portion of the lever 7 and are upset at the ends as customary. One of the levers 10 is deflected laterally at its forward extremity, as shown at 14, in order to straddle the forward extremity of 80 the other lever 10, and the pivot pin 11 passed through and interconnects the levers 10 at the point where one lever straddles the other, *i. e.*, where the levers overlap each other. A spring wire 15 coiled about the 85 pivot 11 has one end portion 16 abutting one of the levers 7 and another end portion 16 abutting the other lever 7, as shown in Fig. 5. This spring forces apart the rear end portions of the levers 7 and thereby 90 normally holds the jaws 6 in an open position. The levers 7 may be slightly recessed adjacent to the pin 11, as shown at 17, in Fig. 5, if this is necessary to permit the rear ends of the levers 7 to be brought together 95 sufficiently to close the jaws 6.

It will be observed that the forked forward end portions of the operating levers are substantially in line with the rear end portions of the corresponding working levers 7 to which they are pivoted, and that said forked portions extend over and sub-

stantially cover the rear end portions of the levers 7 between the pivots 12 and the pivot 11. By this arrangement, the tool may be made of very handy, compact shape without any inconveniently projecting parts.

When the lever handles 10 are forced together they will exert leverage on the rear ends of the levers 7 thereby closing the jaws. When the levers 10 are released, the spring 15 will again open the jaws in an obvious manner. Inasmuch as the pivots 12 are much closer to the pivot 11 than are the portions of the levers 10 grasped by the hands of the operator, and as the jaws in turn are closer to the pivot 8 than are the pivots 12, the tool is quite powerful and pieces of wire, or the like, can be cut, or other work done, with considerable speed and without the expenditure of much energy on the part of the operator in forcing the handles together. By making the handles as levers of the second order, as above explained, the length of the tool is reduced to a minimum without sacrificing the power developed.

Various changes may be made in the details of the construction without departing from the invention as defined in the claims.

What I claim is:—

1. In a hand tool, the combination of a pair of levers pivoted together intermediate of their ends, jaws actuated by said levers, operating levers constructed of sheet metal and having forked forward portions, one of said forked portions straddling the other, a pivot member passing through said forked forward portions of said operating levers at the forward extremities of said levers and pivoting them together, the rear extremities of said first named levers lying in the same plane and being extended into the respective forked portions of said operating levers at the rear of said pivot member and in close proximity thereto, and means for pivoting the rear extremities of said first levers in the forked portions of said operating levers; substantially as described.

2. In a hand tool, the combination of a pair of working levers pivoted together intermediate of their ends, the rear portions of said levers lying in the same plane, operating levers having forked forward end portions, one of said forked end portions straddling the other, a pivot member passing through said forked forward end portions and pivoting said operating levers together, the rear extremities of said working levers being extended into the respective forked end portions of said operating levers with their inner edges in close proximity to said pivot, and means for pivoting the rear extremities of said working levers in the rear parts of the respective forked portions of the operating levers, said forked portions being substantially in line with the rear extremities of said working levers, and ex-

tending over and substantially covering the same; substantially as described.

3. In a hand tool, the combination of a pair of working levers pivoted together intermediate of their ends, operating levers having forked forward end portions, one of said forked end portions straddling the other, a pivot member passing through said forked end portions of said operating levers at the forward extremities of the latter and pivoting said levers together, means for pivoting the rear extremities of said working levers in the rear parts of the respective forked end portions of the operating levers at the rear of said pivot member, said forked portions extending over and being substantially in line with the rear portions of the respective working levers, and a spring supported by said pivot member and acting on said working levers; substantially as described.

4. In a hand tool, the combination of a pair of crossed levers pivoted together intermediate of their ends, jaws actuated by said levers, a pair of operating levers, a pin pivoting said operating levers together at their forward ends, means for pivoting the rear ends of said first named levers to said operating levers intermediate of the ends of said operating levers, and a spring encircling said pivot pin and having end portions to engage the inner edges of said working levers and thereby hold the jaws open; substantially as described.

5. In a hand tool, the combination of a pair of crossed working levers pivoted together intermediate of their ends, jaws actuated by said levers, a pair of operating levers pivoted intermediate of their ends to the rear extremities of the respective working levers, the forward extremities of said operating levers being forked and straddling each other, a pin pivoting together the forked extremities of said operating levers, and a spring encircling said pin within said forked extremities of said operating levers, and having its end portions extending rearwardly from said pin and engaging the inner edges of said working levers adjacent to the pivotal connection of said working levers with said operating levers; substantially as described.

6. In a hand tool, the combination of a pair of crossed working levers pivoted together intermediate of their ends and having recesses at their inner edges adjacent to their rear extremities, jaws actuated by said levers, a pair of operating levers having forked forward portions straddling each other, a pin passing through the forward extremities of said forked portions and pivoting said operating levers together, said pin located between the recesses in the rear ends of said working levers, means for pivoting the rear extremities of said working

5 levers in the rear parts of the respective forked portions of the operating levers, said forked portions being substantially in line with the rear portions of the respective working levers and extending over and substantially covering the same, and a spring encircling said pivot pin within the forked portions of said operating levers and having its end portions engaging the rear extremi-

ties of said working levers to normally separate said jaws; substantially as described.

In witness whereof, I have hereunto set my hand on the 26th day of June, 1914.

WILLIAM A. BERNARD.
